BOILER

Eugene J. Le Claire and Bernard J. Heinzman,
St. Paul, Minn., assignors to Harry F. Joesting,
St. Paul, Minn.

Application March 21, 1946, Serial No. 655,928

2 Claims. (Cl. 122—166)

1

Our invention relates to an improvement in boilers of a type used for developing steam pressure or the like.

Countless types of boilers have been developed for converting water to steam and for similar purposes. Some of these boilers include horizontal boiler tubes and others have included vertical flues. It is an object of the present invention to produce a boiler which is extremely efficient in operation and which utilizes a large proportion of the heat supplied for converting water to steam.

A feature of the present invention resides in the fact that the boiler may be constructed with a minimum of difficulty. Where heat flues of one type or another are employed in heat exchange relation with adjacent compartments containing water, extreme care must be taken to insure the water tightness of the boiler so that it will stand the necessary temperatures and pressures.

It is an object of the present invention to provide an apparatus containing heat flues which may be easily welded together at its assembly operation.

A feature of the present invention resides in the provision of a boiler made from lengths of heavy tubing which may be readily purchased, readily handled and easily assembled. By designing the boiler of material which is readily available the cost of manufacturing the boiler is considerably reduced.

A feature of the present invention resides in the provision of a boiler including an inner and outer shell between which water may be contained. Heat from a suitable source of supply is applied beneath the shells and the innermost shell is open at its lower extremity so that heat may pass into the inner shell to heat the water between the two shells. A top closure or partition is provided for the inner shell and a top closure is also provided for the outer shell which is substantially spaced from the top of the inner tubular member. A draft flue extends through the partition forming the top closure of the inner shell and extends through the outer shell above the partition.

A feature of the present invention is to provide a series of angularly spaced tubular members which extend through the partition member or top closure of the inner shell and are closed at their lower extremity. The lower end of each of these spaced tubular members is connected by a suitable spacing nipple to the inner shell in such a way as to allow water to flow from the bottom of the space between the shells into the lower end of each of the angularly spaced tubular members.

2

Thus I provide a series of columns of water in the path of the heated air passing upwardly into the boiler toward the escape flue.

A further feature of the present invention lies in the provision of a central tubular chamber coaxial with the outer and inner shells and supported from the inner shell by tubes or nipples. This central flue or chamber is closed at its top and bottom ends, but water may circulate there-through by means of the supporting nipples.

A further feature of the present invention resides in providing a central chamber or flue of somewhat larger diameter than the escape flue extending through the partition or top closure of the inner shell and in placing the central flue immediately below the entrance to the escape flue. As a result the heated air travelling through the boiler must travel in a tortuous path in order to leave the boiler by way of the escape flue.

An added feature of the present invention lies in providing a steam outlet in the form of a T connection extending through the outer shell above the top of the inner shell. This T connection provides a pair of opposed steam inlets which equalize one another and which produce a smooth and even flow of steam through the outlet.

These and other objects and novel features of our invention will be more clearly and fully set forth in the following specification and claims.

In the drawings forming a part of our specification:

Figure 1 is a vertical sectional view through the boiler showing the construction thereof.

Figure 2 is a transverse sectional view through the boiler, the position of the section being indicated by the line 2—2 of Figure 1.

Figure 3 is a transverse section through a portion of our boiler, the position of this section being indicated by the line 3—3 of Figure 1.

The boiler A includes an outer shell 10 having an open lower end 11 and a top closure 12. The top closure is preferably domed in order to better withstand pressure. The top 12 is securely welded to the top of the outer shell 10 as indicated.

An inner shell 13 concentric with the outer shell 10 is spaced therefrom to provide a ring-shaped water compartment 14 between the two shells. A ring 15 is welded between the outer and inner shells 10 and 13 to close the lower extremity of the ring-shaped chamber 14.

A partition or top closure 16 is welded or otherwise affixed to the upper end of the inner shell 13. A central aperture 17 is provided in the partition 16 to accommodate the vertical tubular

portion 19 of the heat escape flue. As illustrated in Figure 1 the escape flue is angularly shaped being provided with a transversely extending flue portion 20 connected to the vertical tubular portion 19. The tube 20 extends through an aperture 21 in the outer shell 10 at a point substantially above the partition 16. In the partition 16 is provided a series of angularly spaced apertures 22 through which the upper ends of a series of angularly spaced tubes 23 extend. These tubes are securely welded or otherwise affixed to the partition 16 so as to provide a water tight joint therewith. The lower end of each of the tubes 23 is provided with a closure 24. A nipple 25 connects the lower end of each tube 23 to the inner shell 13. Each nipple 25 extends through the inner shell 13 and through the wall of the tube 23 so as to form a connecting passage therebetween.

A central tubular chamber 26 is arranged coaxially with the shells 10 and 13 and within the angularly spaced series of tubes 23. The tubular chamber 26 is provided with a top closure 27 and a bottom closure 29 and is connected to the inner shell 13 by means of an upper nipple 30 and a lower nipple 31. These nipples extend through the wall of the tubular chamber 26 and through the wall of the inner shell 13 forming a connecting passage between the interior of the chamber 26 and the chamber 14 between the concentric walls 10 and 13.

An inlet connection 32 is provided in alignment with the nipple 31 at the lower extremity of the ring-shaped chamber 14. A steam outlet passage 33 is provided in the outer shell 10 just below the top closure 12 thereof. A nipple 34 extends inwardly from the outlet 33 and provides a support for a T connection 35 having a pair of opposed inlets 36 and 37. This double inlet provides an equalized passage into which the steam may flow, providing a smooth and constant flow of steam from the boiler.

An inspection door 39 closes the inspection door opening 40 in the usual manner. A bridge 41 on the exterior of the boiler bridges the opening 40 and a bolt 42 extends through the door 39 and the bridge 41 to clamp the inspection door in sealed position. When steam pressure is built up within the boiler, this pressure tends to more tightly urge the door 39 against the outer surface of the boiler wall.

The operation of the apparatus is believed obvious from the foregoing description. Heat is applied from beneath the boiler in the usual manner, the boiler illustrated being usually used in conjunction with a gas burner or oil burning device of some type. The heat enters the space defined by the outer shell 10 and is guided by the ring 15 to within the inner shell 13. Within the inner shell the heat may rise about the angularly spaced tubes 23 and about the central tubular chamber 26, these tubes being heated by contact with the heated air. The tubes preferably contain water which is transformed into steam due to the heat applied. The heat strikes the partition or tube 16 and must move laterally to escape through the escape flue 19. A sufficient draft is formed to move the heated air in this manner.

Throughout the entire period of time when the heated air is within the boiler, it is constantly in contact with some heat exchange member to transmit heat thereto. The elbow bent in the

escape flue also tends to withdraw heat from the air passing through the flue to further heat the surrounding water or steam.

In accordance with the patent statutes, we have described the principles of construction and operation of our boiler, and while we have endeavored to set forth the best embodiment thereof, we desire to have it understood that obvious changes may be made within the scope of the following claims without departing from the spirit of our invention.

We claim:

1. A boiler comprising spaced inner and outer shells having closed upper ends and open lower ends, a ring-shaped partition between said shells to close the chamber formed between said shells, a series of circumferentially spaced water tubes open at their upper extremities and extending through the closed upper end of said inner shell, closed lower ends on said water tubes, an individual connecting passage between the lower ends of each of said water tubes and said chamber, a central water tube having flat end plates closing both ends, lateral connecting passage means adjacent each end plate and connecting the upper and lower ends of said central water tube and said chamber, and an escape flue extending through the upper end of said inner shell, through said chamber, and laterally through said outer shell.

2. A boiler comprising spaced inner and outer shells having closed upper ends and open lower ends, a ring-shaped partition between said shells to close the chamber formed between said shells, a series of circumferentially spaced water tubes open at their upper extremities and extending through the closed upper end of said inner shell, closed lower ends on said water tubes, an individual connecting passage between the lower ends of each of said water tubes and said chamber, a central water tube having flat end plates closing both ends, lateral connecting passage means adjacent each end plate and connecting the upper and lower ends of said central water tube and said chamber, and an escape flue extending through the upper end of said inner shell and laterally through said outer shell, said escape flue beginning directly above the closed upper end of said central water tube and spaced therefrom.
